PORTABLE APPARATUS FOR SEPARATION
OF THE CONSTITUENTS OF GASEOUS MIX-
TURESWolcott Dennis, Darien, Conn., assignor to Air
Reduction Company, Incorporated, New York,
N. Y., a corporation of New York

Application December 21, 1942, Serial No. 469,725

1 Claim. (Cl. 261—108)

This invention relates to portable apparatus for separation of the constituents of gaseous mixtures by liquefaction and rectification. While the apparatus is designed specifically for the recovery of oxygen and nitrogen from atmospheric air, it may be employed similarly with units intended for the recovery of the constituents of other gaseous mixtures.

Oxygen and nitrogen are recovered from atmospheric air by well known methods of liquefaction and rectification. The operation is conducted usually in large stationary units, and the products are transported in steel cylinders under considerable pressure. Recently there has been an urgent demand for smaller units and particularly for portable apparatus permitting recovery of the desired gases at or near the point where they are to be used. By employing a portable unit, the necessity for compressing the products into cylinders and the transportation thereof can be avoided.

It is the object of the present invention to provide a simple and practicable structure which permits the transportation of a liquefaction and rectification column with its auxiliary equipment to any place where it may be put into operation readily to supply the desired gases.

Other objects and advantages of the invention will be apparent as it is better understood by reference to the following specification and the accompanying drawing, in which

Fig. 1 is a side elevation of the apparatus embodying the invention; and

Fig. 2 is a plan view thereof.

A major difficulty in the transportation of a liquefaction and rectification column depends upon the fact that an effective column must have substantial height, even in relatively small units. A practical column will be at least nine or ten feet high, and when mounted upon a truck or other transportation vehicle, the column will extend beyond the maximum height permissible in view of underpasses and similar obstructions in existing roads. The present invention obviates this difficulty by mounting the column so that it may be moved readily from its upright operating position to a horizontal position for transportation without disengaging connections with other parts of the equipment such as the compressor, interchangers and dryers which are normally associated with liquefaction columns.

Referring to the drawing, 5 indicates a platform adapted for transportation which may be the floor of a truck, trailer or car, or a portable

base of any character. The column 6 is provided on opposite sides thereof with segments 7 having arcuate surfaces 8 which may be mounted, if desired, upon a guiding track 9 secured to the platform 5. The segments 7 are secured by bolting or otherwise to the column so that the centers of radius 10 of the arcuate surfaces 8 are approximately at the center of gravity of the column. Thus the column may roll on the arcuate surfaces 8 from the upright operating position as shown to the horizontal position indicated in dotted lines on Fig. 1 of the drawing. In this position, the column rests on a cradle 11 secured to the platform 5. The end of the platform is cut away as at 5' to provide a space at least as wide as the column to permit swinging of the column from upright to horizontal position and vice versa.

The details of internal construction of the column form no part of the present invention. There are several types of liquefaction and rectification columns which are available for the purpose of the invention. Such columns require an inlet for the gas which is to be separated and outlets for the separation products. Thus, air under pressure is introduced at the inlet, and oxygen and nitrogen are withdrawn at the outlets. The column 6 is provided, therefore, with an inlet 12 and with outlets 13 and 14 arranged at the sides thereof. The inlet 12 is connected by a flexible pipe 15 with a pipe 16 which is in turn connected to the source of air or other gaseous mixture under pressure. Similarly the outlets 13 and 14 are connected by flexible pipes 17 and 18 with pipes 19 and 20 which deliver the products. When the column is rolled to its horizontal position, the flexible pipes 15, 17 and 18 assume positions similar to the position indicated in dotted lines on Fig. 1 of the drawing. The flexible pipe 15 being connected to the connection 12 and to the relatively fixed pipe 16, and the flexible pipes 17 and 18 being connected to the connections 13 and 14 and to the relatively fixed pipes 19 and 20 adjacent the points of tangency between the arcuate surfaces and the portions of the platform on which they roll, when the arcuate surfaces are at their respective limits of travel, the column 6 may be swung from upright to horizontal position on the platform, or vice versa, to place it in position for operation without disengaging the connections. Because of the arrangement, a column weighing 2,000 to 3,000 pounds can be handled easily by one man.

The auxiliary equipment, such as compressors,

etc., form no part of the present invention and are not illustrated. The devices as employed are conventional and may be mounted on the platform 5 with suitable connections with the pipes 16, 19 and 20. Thus a complete unit can be arranged on a truck or other vehicle to facilitate transportation and operation of the column at the desired place to provide the desired gases.

Various changes may be made in the form and construction of the apparatus without departing from the invention or sacrificing the advantages thereof.

I claim:

In a portable apparatus for separation of the constituents of gaseous mixtures by liquefaction, the combination of a platform adapted for the mounting of a complete liquefaction unit including a rockable liquefaction and rectification col-

umn, supporting segments having arcuate surfaces resting on the platform and secured at opposite sides to the column with the center of radius of the arcuate surfaces approximately at the center of gravity of the column, flexible pipes for the gases entering and leaving the column, connections connecting said flexible pipes with the column, and other connections adapted to connect the flexible pipes to fixed pipes on the platform connected to other parts of the liquefaction unit, the flexible pipes being of such length and the connections being so positioned that the arcuate surfaces may roll on the platform to turn the column from upright to horizontal position on the platform and from horizontal position on the platform to upright operating position without disengaging the connections.

WOLCOTT DENNIS.
